(57) **CLAIM**

The ornamental design for a ceiling fan as shown and described.

DESCRIPTION

FIG. 1 is a top perspective view of a ceiling fan, showing our new design.

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

Portions of the ceiling fan shown in broken lines form no part of the claimed design. The jagged broken break lines shown on the ceiling fan illustrate a symbolic break in length and form no part of the claimed design.
